United States Patent Office.

D. C. PIERCE, OF CLAYTON, NEW YORK.

Letters Patent No. 73,036, dated January 7, 1868; antedated December 25, 1867.

IMPROVED ANCHOR.

The Schedule referred to in these Letters Patent and making part of the same.

TO ALL WHOM IT MAY CONCERN:

Be it known that I, D. C. PIERCE, of Clayton, in the county of Jefferson, and State of New York, have invented a new and improved Anchor; and that the following description, taken in connection with the accompanying drawings hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention consists in constructing the anchor with a single fluke, pivoted in one end of a frame, which serves as a shank for the anchor, a shackle being attached to the opposite end of the frame, all being constructed and arranged in such a manner that the cable cannot "foul" or wind around the fluke or any other part of the anchor, and the fluke made to catch with certainty as soon as the anchor is let down and the vessel moves a trifle under the action of the tide or wind. In the accompanying sheet of drawings—

Figure 1 is a side view of my invention.

Figure 2, a plan or top view of the same.

Similar letters of reference indicate like parts.

A represents the fluke of the anchor, which is formed of a blade-portion, *a*, and what may be termed a head-portion, *b*, the outer surface of which is convex. This fluke is secured by a pivot-bolt, B, between one end of two curved bars, C C, the fluke being balanced, or nearly so, on the pivot-bolt, and the ends of the bars C C extend between lugs or projections *c c*, at each side of the head *b* of the fluke, as shown clearly in fig. 1. The inner side of the head *b*, from which the blade *a* of the fluke projects, is a plane or nearly plane surface. The bars C C are connected at their outer ends by a rod, D, on which a shackle, E, is fitted loosely, and to which shackle the cable is attached. The outer ends of these bars are much further apart than the opposite ends, between which the fluke is pivoted. When the anchor is lowered, the curved bars C C, which perform the function of a shank and a stock, cause the anchor, if either bar strike the bottom first, to turn to a horizontal position, and when the anchor is moved a trifle, under the motion of the vessel, the lower edge of the head *b* will, in consequence of being in contact with the bottom, turn the point of the blade *a* down into the bottom, and cause it to penetrate the same, so as to hold the vessel securely. The fluke may be either of wrought or cast iron. It is believed that cast iron would answer the purpose. The lugs or projections *c c* take all strain off from the pivot-bolt B when the vessel is riding at anchor, as will be fully understood by referring to fig. 1.

Having thus described my invention, I claim as new, and desire to secure by Letters Patent—

The shackle E, in combination with the bars C C, and the pivoted fluke A, all arranged substantially as and for the purpose specified.

The above specification of my invention signed by me, this 24th day of April, 1867.
